UNITED STATES PATENT OFFICE.

DANIEL LINDAHL, OF CHESTERTON, INDIANA.

STOVE.

SPECIFICATION forming part of Letters Patent No. 311,592, dated February 3, 1885.

Application filed March 25, 1884. (No model.)

To all whom it may concern:

Be it known that I, DANIEL LINDAHL, of Chesterton, county of Porter, and State of Indiana, have invented certain new and useful 5 Improvements in Stoves, of which the following is a full, clear, and exact description, that will enable others to make and use the same, reference being had to the accompanying drawings, forming a part of this specification.

This invention relates to improvements in heating-stoves, the object being to economize in the consumption of fuel and retain the products of combustion in the stove and its 15 connecting parts until all of the heat has been abstracted; and it consists of certain novel features in the construction and arrangement of the different parts, as will be hereinafter more fully set forth and claimed.

20 Figure 1 is an elevation of a stove embodying my improved features; Fig. 2, a vertical section; Fig. 3, a horizontal section in the plane xx ; and Fig. 4, a horizontal section in the plane yy , Fig. 1.

25 Referring to the drawings, A represents the base of the stove, A' the heating-cylinder and fire-box, and A² a heating-drum. The base of the stove is hollow, forming the hot-air chamber B, while the partitions a a' on each 30 side of the front part of the cylinder separate the draft-opening a^2 from the hot-air chamber B. The lower end of the cylinder or fire-box sets well down into the chamber-base, in order to keep the same in a highly-heated condition.

35 The vertical hot-air or draft pipes B' B², located at the back part or corners of the stove, communicate with the interior of the cylindrical fire-box by means of the horizontal pipes a^3 a^4 , connecting with the fire-box 40 near the lower end, and the companion horizontal pipes b b' , connected at the top of the cylinder. The connections b b' are provided with dampers, so that the heat may be forced into the vertical pipes through the horizontal 45 connections a^3 a^4 . When supplying fuel to the stove, the dampers in the pipes b b' should be opened, so as to provide a free escape for the gases in the upper part of the cylinder when the door b^2 is open. The heated air will

50 ordinarily pass from the fire-box into the pipes B' B² through the lower connections, the upper ends of said vertical pipes being inserted in the under side and back part of the heat-

ing-drum A², located just above the top of the stove. This drum is provided with a number of diaphragms, C, having each alternate end cut away, so as to leave a passage between alternate ends of the diaphragms and the inclosing-walls of the drum. The heated air escaping from the stove into the drum is thus 60 compelled to pass up and over the first diaphragm, when it strikes and is deflected by the next diaphragm, and so on until the front side of the drum is reached, when the heated air is returned to the front of the stove by 65 passing down through the return-pipes C' C², and from thence discharged into the chamber B in the base of the stove, from which the unconsumed products escape to the outer atmosphere through the smoke-pipe C³, located at 70 the back side of the stove. This construction and arrangement provides a large amount of radiating surface, so that the full benefit of all the fuel consumed is obtained before the products of combustion escape into the outer 75 atmosphere. The bottom of the fire-box just below the grate D is provided with elongated openings corresponding to the openings d in the grate. Fig. 3 shows these openings in line for the admission of air to the fire-box. Fig. 80 4 shows the grate moved to one side, tightly closing the openings and preventing the air from entering the fire-box, thus forming a double grate.

Having thus described my invention, what I 85 claim as new, and desire to secure by Letters Patent, is—

1. In a heating stove, the combination, with a hollow base provided with the partitions a a' , of a heating-cylinder adapted to set well 90 down inside of said chambered base, the vertical smoke-pipes B' B², the horizontal pipes a^3 a^4 , the companion horizontal pipes b b' , the heating-drum A², and the pipes C' C² C³, substantially as and for the purpose set forth. 95

2. In a heating-stove, the combination, with the heating-drum A, connected with the fire-pot, and provided with a number of diaphragms having alternate ends cut away, of the pipes C' C², the chambered base A, and the 100 pipe C³, substantially as set forth.

DANIEL LINDAHL.
